UNITED STATES PATENT OFFICE.

JOSEPH P. CLEAL, OF DAYTON, OHIO, ASSIGNOR, BY MESNE ASSIGNMENTS, TO THE NATIONAL CASH REGISTER COMPANY, OF DAYTON, OHIO, A CORPORATION OF OHIO, (INCORPORATED IN 1906.)

CASH-REGISTER.

No. 833,826.

Specification of Letters Patent.

Patented Oct. 23, 1906.

Application filed March 15, 1904. Serial No. 198,244.

To all whom it may concern:

Be it known that I, JOSEPH P. CLEAL, a citizen of the United States, residing at Dayton, in the county of Montgomery and State 5 of Ohio, have invented certain new and useful Improvements in Cash - Registers, of which I declare the following to be a full, clear, and exact description.

My invention relates to improvements in cash-registers, and has more particular relation to improved indicating devices and improved forms of mechanism for the screens or the flashes which hide the indicators.

One of the particular objects of my invention is to provide a novel arrangement of indicator-tablets which shall be compactly situated to indicate at a series of sight-openings, one sight-opening for each bank or group of keys, whereby the correct indication 15 of the amount of registration may be correctly and easily read through said sight-openings in the manner in which said amounts would ordinarily be written or printed, and I have also provided means for 20 indicating in this manner both at the front and at the rear of the machine.

Another one of the objects of my invention is to provide improved screen or flash mechanism whereby to conceal all the indicating characters which are not necessary for the proper reading of the indication—such, for example, as superfluous indications in the banks of higher denomination which are not used in any particular amount registration.

With these and incidental objects in view the invention consists in certain novel features of construction and combinations of parts, the essential elements of which are set 35 forth in appended claims and a preferred form of embodiment of which is hereinafter specifically described with reference to the drawings which accompany and form part of this specification.

Of said drawings, Figure 1 represents a rear elevation of my machine. Fig. 2 represents a cross-section on the line 2 2 of Fig. 1. Fig. 3 represents a detail elevation of the rack-bar for rotating the main operating-shaft, showing 40 the key-coupler sectionalized. Fig. 4 represents a detail front elevation of one of the indicator-plates. Fig. 5 represents a front elevation of the upper portion of the machine,

showing the indicator mechanism with certain of the registering portions of the machine removed for the sake of clearness; and Fig. 6 represents a top plan view of that portion of the machine which contains the indicator-plates, which portion is shown in Fig. 5.

I have herein shown my improvements as applied to the type of register described in Letters Patent to Thomas Carney, No. 497,860, dated May 23, 1893; but it is of course to be understood that I do not for any reason wish to be limited to this construction 65 of cash-register, since my improvements are equally well adapted to various other forms of cash-registers. I shall describe only so much of this style of machine as is necessary for a clear understanding of my invention 70 and for the general operation of the machine, and for a more detailed description of this kind of machine reference may be had to the aforesaid patent.

Referring to the accompanying drawings, 75 a series of keys 10 are pivoted upon a transverse shaft 11 and are arranged in various banks or groups of values graded in denominations from units of cents to tens of cents and dollars or whatever numerical arrangements may be desired, together with any special keys which may be found convenient to use. These keys are formed at their rear portions with the usual slots 12, which engage the key-coupler 13, which rocks upon 85 the transverse shaft 14. Upon the depression of any key the key-coupler is rocked upward, and by means of a pin 15, mounted upon said key-coupler, which pin plays in a slot 16, formed in a double rack-bar 17, the 90 rocking of the key-coupler reciprocates said bar 17. This rack-bar is slotted at its lower portion 18 to straddle a pin 19, projecting from the main frame of the machine, and said lower portion is normally drawn rearward by means of a spring 20. By means of a lug 21, formed on the rack-bar 17, and a stationary lug 22, formed on the main frame of the machine, on the upward reciprocation of the rack-bar 17 the one set of the teeth of 100 the rack-bar 17 engages with a pinion 23, fast upon the main operating-shaft 24 of the machine, and upon the downward reciprocation of the rack-bar 17 its other set of teeth 105 engages with the same pinion 23, so that upon the complete upward and downward

movement of the key-coupler upon the depression of any key this main operating-shaft 24 is given one complete revolution. Attached to the rearward end of each key 5 is a lifter-plate 25, and these lifter-plates are formed with notches 26, arranged at graduated vertical distances above the lower ends of the keys and arranged to engage a transverse shaft 27 of the registering-frames 28 at 10 different points in the depression of the key, whereby to transmit to said registering-frame a variable rocking movement commensurate with the value of the key depressed, and this variable rocking movement of said 15 registering-frame 28 may be transmitted to any suitable counting devices. (Not shown herein.) All of this mechanism heretofore described is old and is set forth in detail in the aforesaid patent.

20 Resting upon the rear end of each key is a vertical indicator-operating rod 30, which corresponds with the stems of the tablet-indicators described in the aforesaid patent, but having the tablets upon the upper ends of 25 these stems removed and coöperating with another form of indicating mechanism to be described. These rods 30 are arranged to slide vertically in suitable slots formed in the transverse bars 31 and 32, extending between the 30 side frames of the machine. Each of these rods 30 is formed with a horizontal rearwardly-projecting arm 33, which is bent laterally at its rearward end to form a wing 34, (see Fig. 1,) and these wings 34 are arranged 35 to coöperate with antifriction-rollers 35 and 36, (see Figs. 1 and 5,) formed upon the downwardly-extending arms 37 of bell-crank levers 38, pivoted at 39 to a cross-bar 39', extending between the side frames of the machine.

40 The upper arms 40 of these bell-crank levers 38 are formed with slots 41, which engage pins 42, projecting from a series of sliding indicator-plates 43. These indicator-plates 43 are mounted side by side, as shown in Fig. 2, 45 there being one of these plates for each of the aforesaid bell-crank levers 38, and it will be apparent that in order to have this arrangement of the indicator-plates 43 side by side, each connected with one of said bell-crank 50 levers, these bell-crank levers must be displaced laterally one from the other, as shown in Fig. 2, being arranged in gradual lateral displacement from the rear of the machine toward the front of the machine, beginning 55 with the cents-bank of keys. Likewise in order to have the aforesaid wings 34 in position to coöperate with the beveled rollers 35 and 36 upon these laterally-displaced bell-crank levers the arms 33, carrying said wings 60 34, will also have to be of graduated lengths from the cents-bank to the dollar-bank, being of such length as to bring the wings 34 into the path of the said rollers 35 and 36 for their respective bell-crank levers.

65 I have arranged the cents - bank of my

machine with nine keys from one cent to nine cents; but I have arranged said keys to act in pairs upon the bell-crank 38—that is, the one-cent and two-cent keys both act upon the bell-crank lever farthest to the right, (see Fig. 5,) the wing 34 on the one-cent key being normally in line with the antifriction-roller 36 on said bell-crank lever and the wing 34 of the two-cent key being normally in line with the antifriction-roller 70 35 on this same bell-crank lever. Thus it will be observed that since in the normal position of rest of said keys said wings 34 are all at the same height the depression of the one-cent key will raise its rod 30 and cause 80 its wing 34 to contact with the roller 36 and rock the bell-crank lever 38 about its pivot 39, whereas the depression of the two-cent key will raise its rod 30 and cause its wing 34 to contact with the roller 35 at an earlier 85 point in the stroke of the key, thereby moving the bell-crank lever 38 to a greater extent for the purpose to be described. Similarly the three-cent key and the four-cent key act upon the same bell-crank lever, being next 90 from the farthest to the right, (see Fig. 5,) to give said bell-crank lever a graduated movement, the four-cent key moving the same to a greater extent than the three-cent key. Likewise the remaining cent-keys are arranged in pairs to operate upon their respective bell-crank levers to give the same graduated movements, there being one lever for each pair; but of course for the nine-cent key there can only be one bell-crank lever, 95 and consequently there is no roller corresponding to the roller 35 upon this bell-crank lever, but simply a single roller 36, which co-operates with the wing 34 of the nine-cent key to move the bell-crank lever and its attached indicator-plate, as will be seen in Fig. 5, upon the fifth bell-crank lever, counting from the right-hand end of the machine. This arrangement of bell-crank levers one 100 for each pair of keys, with a single nine-cent key acting upon the corresponding nine-cent bell-crank lever, is duplicated in the bank of keys for the units of tens of cents and for the bank of keys for the units of dollars, and it will be apparent that where two keys act 105 upon the same bell-crank lever the rearwardly-extending arms 33 of the aforesaid rods 30 may be graduated in length by pairs, so as to be in correct lateral alignment with the graduated lateral displacement of the bell-crank levers. The usual form of pendent back hangers 48, coöperating with the rear ends 49 of the keys, serve to prevent the operation of more than one key at a time in any bank, all of which is well known in the art 110 and is not described here in detail, since it constitutes no part of my present invention. I will now describe the connections between the aforesaid indicator-plates 43 and their respective indicating-tablets, which are 115

120 125 130

arranged to expose the amount of the registration. These indicating-plates 43 are, as previously stated, mounted side by side, each being formed with two slots 50, through 5 which project two pins 51, extending from the main frame of the machine, these pins serving as supports and guides for the lateral shifting of the indicator-plates. Extending upwardly from each plate 43 is an arm 52, 10 which arm carries upon its upper end a tablet 53, upon which is marked the indicating character, which in this case is one of the numerals corresponding to the value keys. (See Fig. 4.) Since, as heretofore explained, 15 I have arranged to give these indicator-plates 43 a variable movement according to which one of a pair of keys is depressed, I may thus mark upon the aforesaid tablets 53 as many indicating characters as there 20 are separate variable positions of the aforesaid indicator-plates 43, which in this case for all the first eight keys of each group comprises two separate indicating positions—that is, in the cents-bank I may mark upon 25 the tablet attached to the first indicator-plate both the figures "1" and "2" and upon the tablet of the next indicator-plate the figures "3" and "4," and so on, and upon the indicator-plate for the nine-cent key, of 30 course only a single numeral would be placed, being the "9," and this arrangement is duplicated for the other banks. At the top of the machine I have provided two cross-strips 54 (see Figs. 5 and 6) to conceal 35 these indicator-tablets from the front and from the rear of the machine; but these strips 54 are formed with three sight-openings 55, one for each group of keys, through 40 which the indication may be read when the indicator-tablets are moved into position in the manner to be described. A similar series of sight-openings 56 is provided at the rear of the machine, as shown in Fig. 1, in order to display the indication at the rear of 45 the machine, also by means of mechanism to be described. The normal relation between the aforesaid tablets 53 and the sight-openings 55 at the front of the machine is such that no tablets are visible through these 50 sight-openings except certain tablets bearing a zero indication, the purpose of which will be set forth later. When, however, upon the operation of any key the bell-crank-lever corresponding thereto is rocked in the manner 55 previously described, the indicator-plate 43 attached thereto is shifted to the left, (see Fig. 5,) thereby carrying into indicating-position one of the indicating characters upon the tablet 53, the correct display depending 60 upon the extent of movement of said indicator-plate, as will be obvious from the description of the mechanism heretofore given. Thus when the one-cent key is depressed the indicating-plate corresponding thereto is given a certain extent of move- 65

ment enough to carry the figure "1" into view at the right-hand sight-opening 55, (see Fig. 5,) whereas if the two-cent key is depressed this same indicator-plate 43 is given a greater extent of movement and the figure 70 "2" upon the same tablet 53 is brought into view at the sight-opening 55. The duplication of this arrangement throughout will be apparent.

In order to provide a zero indication in the 75 case in which no key in the cent-bank is depressed, I have made the tablet 53 of the indicator-plate for the one-cent and two-cent keys of slightly greater width than the ordinary tablets for the purpose of having 80 marked thereon a zero, and in the normal position of this tablet this zero stands directly opposite the sight-opening for the cent-bank, so that if no key in the cents-bank is operated this zero will show through said opening. 85 When either the one-cent or two-cent key is operated, it will of course be apparent that this zero will be moved out of indicating position with the movement of the tablet upon which it is carried. When any of the other 90 keys in this cents-bank are operated, this zero-mark of course still remains opposite the sight-opening 55; but since the indicator-plate 43 for the one-cent and the two-cent keys is the farthest toward the rear of the 95 machine in order to connect with its corresponding bell-crank lever, which is also the farthest to the rear of the machine, as heretofore explained, it will thus be obvious that the indicator-plates 43 for the other keys of 100 the cents-bank will be in front of the indicator-plate for the one-cent and two-cent keys, so that when shifted to the left upon the operation of any such keys their tablets will move into indicating position in front of the 105 zero-mark upon the one-cent and two-cent tablet, thus obscuring this zero-mark from view until these subsequently-operated tablets are returned to normal position in the manner to be described. In the bank of tens 110 of cent-keys I have provided a different arrangement for the zero-indicator, comprising a separate and distinct tablet 56^a, (see Fig. 5,) upon which is marked a zero, said tablet being mounted upon a sliding frame 57, 115 which is normally drawn to the right by means of a spring 58, which holds the zero-indicator normally in view through the sight-opening 55. This frame 57 has formed on its lower side an arm 59, which projects from 120 the front to the rear of the machine across the path of all of the upwardly-extending arms 52 of the tablets of the ten-cent bank, so that when any of said tablets are moved into indicating position their respective arms 125 52 will contact with said rearwardly-extending arm 59 and force the frame 57 to the left against the tension of the spring 58, thereby carrying the zero-indicator out of indicating position and allowing the other tab- 130

let to move into indicating position. It will of course be obvious that no zero indication is necessary upon the dollar-bank. From this construction it will be apparent that if 5 only a key in the dollar-bank is operated its corresponding numeral will be shown at the dollar sight-opening and the two zero-indicators will be shown at the ten sight-opening and the unit sight-opening in the manner 10 shown in Fig. 5 and if only a key in the tens-bank is operated nothing will be indicated at the dollar sight-opening. The proper numeral will be indicated at the ten sight-opening, and the zero of the cent sight-opening 15 will complete the proper indication. Likewise if only a key in the cents-bank is operated its corresponding numeral will be indicated at the cents sight-opening and a zero would be in position to indicate in the tens sight-opening; but by means of the screen mechanism, to be later described, both this zero and the sight-opening for the dollar-bank are obscured, so that only the indication 20 of the cents-numeral remains exposed.

25 In order to hold the indicator-plates 43 in the position to which they are moved, I have provided latching mechanism, as follows: Each of the indicator-plates 43 is formed with two upwardly-extending projections 60, 30 adapted to be engaged by the nose 61 of the latch 62, fast upon a shaft 63, suitably journaled in plates extending from the side frames of the machine. This latch is the shape of a bail extending transversely across all of the 35 indicator-plates 43, so that upon the movement of any one of said indicator-plates to the left it will be latched in either one of its indicating positions by means of the engagement of one of the projections 60 with the 40 nose 61 of the latch 62, and a spring 64, engaging an upwardly-extending arm 65, fast to the latch 62, normally tends to hold said latch in engagement with the projection 60. Fast upon the forward outer end of the shaft 45 63 is a crank-arm 66, to which is attached a downwardly-extending link 67, (see Figs. 2 and 5,) and the lower end of this link 67 is pivoted to a curved lever 68, pivoted to the main frame at 69 and having a rearwardly-extending arm which is drawn downward by 50 a spring 70 and a forwardly-extending arm provided with a nose 72, which engages a cam-disk 73, fast upon the main revolution-shaft 24. It will thus be evident that upon 55 the operation of any key and the consequent rotation of the shaft 24 in the direction of the arrow shown in Fig. 2 the disk 73 will cam the forward arm of the lever 68 downward, thereby operating, through the link 67, to rock the 60 shaft 63, withdraw the nose 61 of the latch 62 from engagement with the projections 60 of any previously-operated indicator-plate, and thus allow said indicator-plates to return to normal position under the spring tension of 65 returning devices to be described, and as soon

as the cam-disk 73 has rotated far enough to allow the lever 68 to return to normal position the newly-displaced indicator-plates 43 are now in position to have their projections 60 engaged by the latch 62, so that these 70 newly-displaced indicator-plates will now remain in indicating position until the next operation of a key, and, of course, in the manner usual with this class of machines, a key in each bank may be simultaneously operated 75 so as to display the complete indication, and all of the indicator-plates will be held latched in this indicating position.

The means for effecting the return of the indicating-plates to normal position when released from the aforesaid latch 62 is shown in Fig. 1. At the rear of each group of the aforesaid bell-crank levers 33 there is mounted upon the upper side of the cross-strip 39' a sliding plate 80, which has extending upward 35 from it a series of projections 81, engaging pins 82, formed on the rear side of the upper arms 40 of the aforesaid bell-crank levers. These plates 80 are formed with slots 80^a, (indicated by dotted lines in Fig. 1,) engaged by 40 pins 83, which serve to guide said plates 80 in their lateral shifting movements. Springs 84, one for each plate 80, normally draw said plates toward the right-hand side of the machine, (the left in Fig. 1,) so as to keep the 45 projections 81 in contact with the pins 82. It results from this construction that when any bell-crank lever is rocked in the manner heretofore described to carry its indicating-plate into position to expose its indicating-tablet the pin 82, acting upon the projections 81, will displace the plate 80 laterally against the tension of its spring 84, so that upon the release of the indicator-plate 43 from the 50 latch 62, as heretofore described, the pressure of the projections 81 on the pin 82 causes the return of the bell-crank lever to its normal position, and thereby also carries the indicator-plate 43 to normal position. This arrangement of the plate 80 is of course 55 duplicated for each group of bell-crank levers; but in the dollar-bank in order to return the bell-crank lever corresponding to the nine-dollar key I have attached, at the pivotal axis 39 of said bell-crank lever an upwardly-extending L-shaped arm 87, which is bent forward at its outer end 88 in such manner as to bring this outer end into engagement with the projection 81, extending upward from the plate 80 for this bank, whereby upon the 60 rocking of the bell-crank lever of the nine-dollar key the L-shaped arm 87 will also rock, and the bent portion 88, acting against the projection 81, and thereby laterally displace the plate 80 against the tension of its 65 spring just as the pins 82 do in the case of the other bell-crank levers, and thereby effecting the return of the nine-dollar indicating-plate to normal position. This L-shaped arm 87 is used for the nine-dollar key instead of 70

using a projection such as 81 for the other keys on account of the lack of room due to the proximity of the side frame.

Since it is desirable to indicate at the sight-openings 56 at the rear of the machine, as well as at the sight-openings 55 at the front of the machine, I have provided mechanism which I shall now describe for effecting this.

Each of the indicator-plates 43, corresponding to the bank of cents-keys, is provided with two of the tablet-supporting arms previously referred to, one of these arms 52 carrying the tablet with the indicating characters arranged to be exposed at the front sight-opening 55 and the other arm 52^a carrying a similar tablet for indicating at the sight-opening 56 at the rear of the machine, and of course at the opposite end of the machine, in order to have the correct order of figures from left to right. The indicator-plate 43 for the one-cent and two-cent keys of the cents-bank is shown in detail in Fig. 4, and it will be observed that the tablet for the front indication bears the zero-mark, as heretofore explained, whereas the tablet for the rear indication bears no zero-mark, the zero-mark for this indication being carried upon the "9" tablet for a reason to be explained. As will be observed also from Figs. 2 and 4, certain of these arms 52 and 52^a do not extend straight upward from the indicator-plate 43, but near their lower ends are bent horizontally at right angles and then again bent upward at right angles. The purpose of this in the cents-bank is to bring the tablets nearer the front sight-opening 55 and also to permit the insertion back of these cents-tablets of the series of dollar-tablets, which are of course connected with the upwardly-extending arm 52^a of the indicator-plates 43 for the dollar-bank and obviously must be arranged to indicate at the rear opening 56, which is directly opposite the front opening 55 of the cents indication, so as to have the correct indication at the rear from left to right. Since the indicator-plates 43 for the dollar-bank are thus nearest the front of the machine, their respective arms 52^a for the back indication are likewise bent laterally, as shown in Fig. 5, so as to bring their respective indicator-tablets near the rear opening 56 and at the same time slide free of and in the rear of the cents-indicating tablets, which are exposed at the front of the machine. The indicator-plates 43 being, as before explained, in numerical order from the rear to the front of the machine, it will therefore be apparent that for the cents sight-opening 56 at the rear of the machine the zero-mark must be placed upon the "9" tablet, which is consequently widened for that purpose, so that the movement of the cents-tablets for any amount below nine may bring this tablet in front of the zero-mark on the "9" tablet, which of course could not occur if the zero-mark were upon

the one-cent and two-cent tablet, as in the case of the front indication, since the one-cent and two-cent tablet is the one which is nearest the rear of the machine.

In the case of the indication for the ten-cent bank it will at once be apparent that the same numerals may be used at the back as at the front of the machine, there being no necessity of any reversal of position, as in the case of the cents or the dollars. Therefore I have simply provided my tablets for the ten-cent bank with duplicate numerals on the front and on the back, the front numerals of course indicating at the front sight-openings 55 and the rear numerals indicating at the rear sight-opening 56. Likewise the zero-indicator for this ten-cent bank, which has been previously described, has a zero-mark upon its rear to show a zero-numeral at the rear of the machine.

I will now describe my flash mechanism, the purpose of which is to conceal the indicators upon the initial movement of any of the keys and after the operation of the key to expose only such of the indicators as is necessary for a correct reading of the same without the display of unnecessary zeros. This mechanism is shown in Fig. 1 and comprises separate screen-plates 90, 91, and 92 for each of the three sight-openings 56 at the rear of the machine—namely, the cents, the dimes, and the dollar openings, respectively. These screen-plates are mounted to slide upon the vertical cross-plate 54, and the plates 90 and 91 have at their tops laterally-extending arms 93 for the purpose of abutting against the screen-plates next them, and it will thus be obvious that the movement of the screen-plate 90 to the left into screening position over the sight-opening 56 will by means of its arm 93 also move the screen-plate 91 over its sight-opening, and the movement of this plate 91 will by means of its arm 93 also move the screen 92 over its sight-opening, and, conversely, the movement of the screen 92 to reveal its sight-opening will likewise cause the movement of the screens 90 and 91 to reveal their sight-openings; but the movement of the dollar-screen 92 to the left may take place independently of the other two screens and the movement of the screen 91 to the left may take place independently of the screen 90, but will carry with it the screen 92. The screen 90 has attached to its lower side a lever 94, pivoted to the cross-strip 95 at 96, and the lower end of this lever 94 is connected to a link 97, which is pivoted at 98 to the upper end of a lever 99, pivoted at 100 to the cross-strip 39'. A spring 101 connects the lower end of this lever with the end of the previously-described plate 80, which operates in connection with the bell-crank levers of the cents-bank to return the same to normal position. A spring 102 is connected to the said lever 94 and

tends to draw the same to the left in such manner as to carry the screen 90 over its corresponding sight-opening. The screen-plate 91 has connected to it a lever 103, pivoted to the cross-strip 39' at 104, and a spring 105 connects this lever with the plate 80, which returns the bell-crank levers of the dimes-bank to normal position. The screen-plate 92 has connected to it a lever 106, pivoted to the cross-strip 39' at 107, and at an intermediate portion of this lever there is pivoted a bar 108, which is supported by a pin 109, projecting from the cross-strip 95, and by means of a slot 110 may have a lateral movement under the influence of a spring 111, the right-hand end of which is attached to the plate 80, which returns the bell-crank levers of the dollar-bank to normal position. From this construction it results that when a key in the cents-bank is operated and its corresponding plate 80 is forced to the right (referring to Fig. 1) the spring 101 is put under tension, and obviously through the lever 93 the link 97 and the lever 94 moves the screen-plate 90 to the right, exposing the indication of the cents-bank. This movement, however, is against the tension of a spring 102, which tends to return the screen-plate 90 to screening position. Therefore the spring 101 is necessarily of greater strength than the spring 102. When a key in the dimes-bank is operated, the movement of its corresponding plate 80 acts, through the spring 105, upon the lever 103, and thereby carries its screen-plate 91 to the right, thus exposing the indication in the dimes-bank, this movement of the lever 103 being against the tension of a spring 112, which tends to return said lever to the left, so as to carry the screen-plate 91 normally into screening position. Since the movement of the screen-plate 91 to the right in this manner also moves the screen-plate 90 to the right, it results that the spring 105 must be of greater strength than the combined strength of the springs 102 and 112, so as to reveal the indication at both the dimes and the cents banks. If a key in the dollar-bank is operated, the movement of its corresponding plate 80 acts upon the spring 111 to pull to the right the bar 108, and thereby pull the lever 106 to the right, thus moving the screen-plate 92 to the right and exposing the dollar indication, and of course this movement of the screen-plate 92 to the right moves both the screen-plates 90 and 91 to the right, thus exposing their sight-openings, and since such movement is against the tension of both springs 102 and 112 the spring 111 must also be of greater strength than the former two springs combined. Since, as heretofore explained, upon the initial operation of any key the aforesaid latch 62 releases all the indicator-plates 43 and allows the three plates 80 to return the bell-crank levers for the various banks to normal posi-

tion, such return of the plates 80 to normal position will release the tension of their respective springs 101, 105, and 111 in case they have previously been put under tension by the operation of a key in any one of the respective banks, and thereby the springs 102 and 112 will act upon the indicator-plates 90 and 91 to draw the same into concealing position, thereby also moving the screen-plate 92 into concealing position. It will thus be apparent from this construction that at the beginning of operation of any key any of the screen-plates which they have moved into position to reveal its corresponding indicator will be returned to normal screening position. Furthermore, if a key in the cents-bank is operated only the screen-plate 90 will be moved into exposing position, the other two screen-plates 91 and 92 remaining in concealing position, so that the only figure which shows is the amount of the cents registration without any confusion arising from the presence of superfluous zeros. If a key in the dimes-bank alone is operated, the screen-plate 91 will be moved to the right into exposing position, as heretofore explained, thereby carrying with it the screen-plate 90, and thus revealing the zero indication in the cents-bank, which, taken in connection with the one numeral of the dimes-bank, will of course give the correct indication for the amount of registration; but in such case the screen-plate 92 remains in concealing position, as heretofore explained. In case a key in the dollar-bank alone is operated its corresponding numeral will be exposed at the dollar-opening by the movement of the screen-plate 92 to the right, which movement carries both the screen-plates 90 and 91 to the right, thus revealing the zero indications both in the cents-bank and in the dimes-bank, making a correct indication of the number of dollars registered in the manner in which the figures would ordinarily be written. Of course if a key in each of the several banks is operated simultaneously all of the indicators will be exposed simultaneously in the manner above described with the figures exposed in the correct order and in the manner in which they would ordinarily be written.

In order to provide for the screening and exposing of the indicators at the front of the machine, I have provided a duplicate set of screen-plates 120, 121, and 122 (see Figs. 5 and 6) for the sight-openings 55 at the front of the machine, covering the cents-indicators, the dimes, and the dollar indicators, respectively, and in order that the screen-plate 90 may move its corresponding screen-plate 120 I have provided a link 123, which connects the horizontal arms 124, which extend inward from the screen-plates 90 and 120 and over the rows of indicator-tablets. Likewise by means of a link 125 the screen-plates 120

92 and 122 are connected to move simultaneously, and by means of a cross-strip 126 the screen-plates 91 and 121 for the dimes indication are also connected, it being evident 5 that these cross connections are such that upon the movement of any of the rear screen-plates into concealing position it will likewise carry in concealing position its corresponding screen-plate at the front sight- 10 openings.

While the form of mechanism here shown and described is admirably adapted to fulfil the objects primarily stated, it is to be understood that I do not care to confine myself 15 to any one form of embodiment of the invention here disclosed, for it is susceptible of embodiment in various forms all coming within the scope of the claims which follow.

Having thus described my invention, what 20 I claim as new, and desire to secure by Letters Patent, is—

1. In a cash-register, the combination with a series of keys, of a plurality of indicating- 25 plates therefor, a certain portion of each of which plates bears a plurality of indicating characters; and means connected with the keys for moving into one and the same indicating position common to the entire group of plates the character corresponding to the 30 key depressed.

2. In a cash-register, the combination with a series of keys arranged in groups, of a plurality of indicating-plates for each of said groups a certain portion of each of which 35 plates bears a plurality of indicating characters; and connections between the keys of each group and the corresponding indicator-plates for this group arranged to give said plates a variable movement whereby to bring to one and the same indicating position common to this entire group the character corresponding to the key depressed.

3. In a cash-register, the combination with a series of depressible key-levers denominationaly grouped, of laterally-slidable indicator-plates similarly grouped, there being a plurality of such plates for each denominational group and each plate having a display part or portion bearing a plurality of indicating characters, and operating connections 45 between the respective groups of key-levers and their respective groups of indicating-plates with provisions for variably shifting a plate by coaction with a plurality of keys of 50 a group.

4. In a cash-register, the combination with a series of keys arranged in groups, of a plurality of indicating-plates for each of said groups a certain portion of each of which 55 plates bears a plurality of indicating characters; connections between the keys of each group and the corresponding indicator-plates for this group arranged to give said plates a variable movement whereby to bring to one and the same indicating position at the front

of the machine the character corresponding to the key depressed; and means connecting said indicator-plates with corresponding indicators for indicating at the back of the machine.

5. In a cash-register, the combination with a series of keys arranged in groups, of a plurality of indicating-plates for each of said groups a certain portion of each of which plates bears a plurality of indicating characters; connections between the keys of each group and the corresponding indicator-plates for this group arranged to give said plates a variable movement whereby to bring to one and the same indicating position at the front 80 of the machine the character corresponding to the key depressed said characters being arranged in proper reading order from left to right; and means connecting said indicator-plates with corresponding indicators for indicating in the proper order at the back of the machine.

6. In a cash-register, the combination with a series of keys arranged in groups, of a casting having a series of sight-openings one for 90 each of said groups; a plurality of indicating-plates for each of said groups certain portions of each plate bearing a plurality of indicating characters; a bell-crank lever connected to each plate; a plurality of projections formed 95 upon each of said bell-crank levers; and operating projections connected with each key arranged to coöperate with its corresponding projection upon said bell-crank levers whereby a plurality of said keys operate upon a single bell-crank lever and give its indicator-plate variable movements corresponding to the key depressed.

7. In a cash-register, the combination with a series of keys arranged in groups, of a casting having a series of sight-openings one for each of said groups; a plurality of indicating- 105 plates for each of said groups certain portions of each plate bearing a plurality of indicating characters; a bell-crank lever connected to each plate; a plurality of projections formed upon each of said bell-crank levers; operating projections connected with each key arranged to coöperate with its corresponding projection upon said bell-crank 110 levers whereby a plurality of said keys operate upon a single bell-crank lever and give its indicator-plate variable movements corresponding to the key depressed; and connections between said indicator-plates and a 115 corresponding set of indicators controlled in the same manner by said keys whereby to indicate both at the front and at the rear of the machine.

8. In a cash-register, the combination with a series of keys arranged in groups, of a casting having a series of sight-openings one for each of said groups; a plurality of indicating- 125 plates for each of said groups certain portions of each plate bearing a plurality of indicating 130

- characters; a bell-crank lever connected to each plate; a plurality of projections formed upon each of said bell-crank levers; operating projections connected with each key arranged to coöperate with its corresponding projection upon said bell-crank levers whereby a plurality of said keys operate upon a single bell-crank lever and give its indicator-plate variable movements corresponding to the key depressed; connections between said indicator-plates and a corresponding set of indicators controlled in the same manner by said keys whereby to indicate both at the front and at the rear of the machine; latching projections formed upon each of said plates to hold the same in indicating position; a latch coöperating with said projections; and means connected with all of said keys for operating said latch.
9. In a cash-register, the combination with a series of keys arranged in groups of graded denominations, of a series of individual indicator mechanisms for each group also arranged in graded denominations; of individual screens for each of said indicator mechanisms; means connected with said keys for moving all of said screens into concealing position upon the beginning of operation of any key; and means also connected with said keys for moving into exposing position the screen of the group of the key operated together with the screens of all lower denominations and for leaving in concealing position the screens of all higher denominations.
10. In a cash-register, the combination with a series of keys arranged in groups, of an indicating mechanism for each group ar-

ranged to indicate at the front and rear of the machine; an individual screen for each indicating mechanism; means connecting the screens of the corresponding groups at the front and the rear of the machine; and means connected with said keys for operating only a predetermined number and leaving unoperated the remainder of said screens according to the group of the key depressed.

11. In a cash-register, the combination with a group of keys, of a plurality of indicating devices each having a plurality of indicia thereon, and means controlled by the keys, which when operated will carry any of the indicia on any indicating device to appear in a common viewable position.

12. In a cash-register, the combination with a group of key-levers, of a plurality of indicators each having a plurality of separate amounts thereon, and means operated by the key-levers for moving the indicators differentially to exhibit any amount on any indicator at a common sight-opening.

13. In a cash-register, the combination with a group of keys, of sliding indicating-plates each having a plurality of separate indications thereon, and connections between the keys and plates for differentially sliding the latter to bring any indication on any plate to a common line of sight.

In testimony whereof I affix my signature in the presence of two witnesses.

JOSEPH P. CLEAL.
